DESIGN FOR A FORE END FOR GUNS

Arthur Charles Fink, Rock Township, Jefferson
County, Mo.

Application July 6, 1939, Serial No. 85,858

Term of patent 14 years

To all whom it may concern:

Be it known that I, Arthur Charles Fink, a citizen of the United States, residing at Rock Township, Highway 141, in the county of Jefferson and State of Missouri, have invented a new, original, and ornamental Design for a Fore End for Guns, of which the following is a specification, reference being had to the accompanying drawing, forming part thereof.

Figure 1 is a bottom perspective view of a fore end for guns, showing my new design.

Figure 2 is a top plan view thereof.

Figure 3 is a side elevational view thereof, the opposite side being substantially the same as shown.

Figure 4 is an enlarged transverse vertical sectional view taken through Figure 3 approximately on the line 4—4.

I claim:

The ornamental design for a fore end for guns, as shown.

ARTHUR CHARLES FINK.
